UNITED STATES PATENT OFFICE

MAURICE F. GRIFFIN, OF LOS ANGELES, CALIFORNIA

DESIGN FOR AN AUTOMOBILE TRUNK

Application filed September 16, 1929. Serial No. 32,763. Term of patent 3½ years.

To all whom it may concern:

Be it known that I, MAURICE F. GRIFFIN, a citizen of the United States, residing in Los Angeles, in the county of Los Angeles and State of California, have invented a new, original, and ornamental Design for an Automobile Trunk, of which the following is a specification, reference being had to the accompanying drawing, forming part thereof.

The figure is a perspective view of a trunk showing my new design.

The essential features of my design consist of metal strips on the body and cover of the trunk at the end edges thereof, and metal strips on the top and front side of the body

which meet and form, respectively, a saddle-shaped space on the cover and a rectangular-shaped space on the front side of the body, the latter being a continuation of the saddle-shaped portion, the said metal strips having inlaid therein ribbons of fabric which harmonize in color with the fabric covering the trunk, the saddle and rectangular-shaped spaces outlined by the metal strips being covered with material of a color different from that of the fabric covering the trunk.

I claim:

The ornamental design for an automobile trunk, as shown and described.

MAURICE F. GRIFFIN.
